UNITED STATES PATENT OFFICE.

ALLEN NOEL, OF COLUMBUS, OHIO.

CIGAR-MAKING MACHINE.

Application filed March 8, 1921. Serial No. 450,780.

My invention relates to cigar making machines and more particularly to a rolling apparatus. In cigar making the bunch breaking operation as usually performed 5 consists in collecting in the operator's hand, sufficient filler material to form a cigar of the desired size, which filler material while being held in straight parallel relation is broken off to approximately the desired 10 length of the cigar. This filler material is then wrapped tightly in a section of tobacco leaf known as the binder. In order that the cigar shall draw readily and burn uniformly, it is necessary that the filler material 15 shall be uniformly distributed and evenly arranged without being twisted. For successful hand rolling of cigars, it is therefore necessary that the filler material be of full 20 length and short length filler and scrap cannot be successfully made into cigars of uniform quality. The present invention is designed to enable the rolling of short length 25 filler material and scrap tobacco without distorting nor twisting the body of filler material to such extent as to interfere with the passage of air therethru.

While machines have heretofore been devised and successfully used for rolling cigars, the object of the present invention is 30 to simplify the structure as well as the means and mode of operation of such devices, whereby they will not only be cheapened in construction, but will be more efficient in operation, uniform in production, 35 automatic in action, rapid and capable of being successfully operated by persons unskilled in the art of cigar making.

A further object of the invention is to 40 provide improved means for bunching the filler material, and holding it compactly yet without distortion while the binder leaf is being wrapped thereabout.

A further object of the invention is to 45 provide an apparatus which will rotate the bunch of filler material to wrap the binder thereabout with uniform tension.

A further object of the invention is to 50 provide a device which will roll cigars automatically of substantially uniform size.

With the above primary and other incidental objects in view as will more fully appear in the specification, the invention 55 consists of the features of construction, the parts and combinations thereof, and the mode of operation or their equivalents as herein-after described and set forth in the claims.

Referring to the drawing, Fig. 1 is a top plan view of the assembled machine forming the subject matter hereof. Fig. 2 is a side elevation thereof. Fig. 3 is a side elevation of the pedal operated pawl and ratchet drive means.

Like parts are indicated by similar characters of reference thruout the several views.

The cigar rolling or "bunch breaking" 60 machine forming the subject matter hereof may be mounted in any suitable manner, preferably upon supporting legs or on a table having laterally extending leaves or shelves to afford supports for the raw material and finished product. However, the apparatus may be mounted in groups or series upon a continuous table or counter, or otherwise supported as may be found most convenient. The present device is designed 65 for treadle or foot power operation, two treadles being used, one of which is applied to compress the bunch of filler, while the other treadle actuates the mechanism to roll the compressed body and wind the binder 70 leaf thereabout. It will be obvious that motor power may be applied in lieu of these 75 treadle operations.

Referring to the drawings, 1—1 comprises 80 the bed of the main body from which project upward posts or standards 2—2 to afford support for a series of aprons or traveling belt supporting rollers. Journalled in the bearing posts or standards 2 are rollers 85 3 and 4 while at the forward end of the main frame is a third roller 5 of somewhat greater diameter journalled in an adjustable bearing head 6. This bearing head 6 is 90 slidingly mounted upon guide rods or ways 7 extending intermediate a pair of posts or standards 2^a and is adjusted to and fro by means of adjusting screws 8. Passing about the rollers 4, 3 and 5 is an endless traveling belt or apron 10. The bottom or base 95 1 of the machine comprises a platen or support over which the apron or belt 10 travels and by which it is supported to prevent sag. Intermediate the rollers 4 and 3 and tangentially to such rollers is a supporting shelf 100 or platen 11, which also supports the upper length of the belt or apron 10 to prevent sag or slack intermediate the rollers 4 and 3. However, this belt or apron is of sufficient length that intermediate the rollers 5 and 6 is formed a bight or loop 12. Being 105 supported throughout substantially its entire path of travel, except between the top

of the rollers 5 and 3, all the slack or sagging of the apron or belt will be concentrated at this point.

Pivoted to the main frame at the point 13 intermediate the rollers 5 and 3 is an oscillatory frame comprising the rock arms 14, interconnected at their upper and free ends by an intermediate roller 15, of comparatively small diameter. The apron or belt passes over this roller 15 intermediate the arms 14, in its passage from the roller 3 to the roller 5, with the slack or sag forming the aforementioned bight between such roller 15 and the roller 3. This swinging frame is actuated toward the roller 3 by means of a foot treadle shown in the drawing, which is operatively connected by the link 16 with a lug or finger 17 projecting from the swinging arm 14. Upon the depression of the 20 pedal, the link 16 is drawn downward, oscillating the swinging frame rearwardly toward the roller 3, thereby closing the bight in the apron or traveling belt by contracting the mouth of such bight as shown by 25 dotted lines in Fig. 2. In operation, the filler material whether of long or short length, scraps or broken pieces are distributed substantially uniformly within the open bight or sag of the apron or belt. The foot 30 pedal is then depressed to draw the swinging frame rearwardly until the roller 15 approaches quite closely to the periphery of the roller 3. This serves to contract the bight or loop of the belt or apron about the 35 deposited filler material, compressing such material uniformly. Before depositing the filler material and contracting the loop or bight thereabout, the binder leaf section is preferably laid flat upon the top surface of 40 the belt or apron, extending rearwardly from the roller 3 over the table or platen, with its forward end extending downwardly within the loop or bight intermediate the roller 3 and roller 15. The forward end of 45 the binder leaf thus extends within the loop and in contact with the deposit of filler material. While the loop is being held contracted and the bunch of filler material under compression by the pressure of the operator's foot upon the treadle controlling the 50 swinging frame, the rollers are actuated to advance the belt or apron.

As shown in the plan view Fig. 1, the journal shafts of the rollers 3 and 4, extend 55 beyond their bearings in the upright posts 2 and carry small bevel gear pinions 19 and 20, intermeshing with corresponding pinions 21 and 22 upon a longitudinally disposed shaft 23, mounted in suitable bearings 60 in the main frame. These rollers 4 and 3 are thus rotated in unison. The drive shaft of the roller 3, carries in addition to its bevel gear pinion, a spur pinion 26, with which meshes a driving gear 27 upon a power shaft 65 28, journalled in bearings 29 and 30 upon the

main frame. This power shaft 28 carries fixedly mounted thereon a ratchet wheel 31 and adjacent thereto an oscillatory lever 32, having a pawl 33 operatively engaged with the ratchet wheel 31. A link or rod 34 connects the oscillatory arm 32 with a foot treadle beneath the apparatus, upon the depression of which, the connecting rod 34 is drawn downward thereby oscillating the rock arm 32 downwardly and causing the pawl 33 to advance the ratchet wheel 32, and thereby rotate the power shaft 28. The power shaft 28 being geared direct to the shaft of the roller 3 rotates the roller 3 and with it the roller 4, by means of the intermeshing 70 gears to advance the belt or apron. The travel of the belt or apron thru the loop or bight from the roller 3 to the roller 15, which bight is being held contracted about the bunch of filler material, causes a corresponding rotation of such bunch of filler material, and simultaneously advances the section of binder resting upon the apron about such body of filler material. The rotation of the body of filler material and the 80 winding of the binder leaf thereabout being uniform thruout their length affords a uniformly compact cigar body without twisting the individual strands of filler, or winding them one about another. 90

While rolling cigars by hand requires considerable skill and dexterity, the operation can be performed with the aid of the heretofore described machine, by any one possessing sufficient judgment to distribute 100 the filler material approximately uniformly throughout the length of the bight or loop, and place in position the binder leaf. The cigars wrapped will be of uniform size and compression and the binder leaf will be 105 smoothly distributed.

By adjusting the forward roller 5 toward or from the roller 3 by means of the adjusting screws 8, greater or less amount of sag may be permitted in the belt or apron, thereby increasing or decreasing the size of the bight or loop, and consequently the diameter of the finished product. As a convenience to the operator, a sack or apron 110 may be provided at the front of the machine 115 to contain a supply of loose cigar materials.

It will be obvious that in lieu of the pawl and ratchet movement for operating the traveling belt or apron, motor power may be applied and intermittently connected by 120 means of clutch mechanism. The application of motor power is so obvious as not to require illustration.

To avoid friction, the supporting platens or tables upon which the apron or belt rests 125 in its travel from one roller to another, may be provided with small rollers, or other movable support. The purpose of these supports for the belt or apron is to prevent the weight of the belt or apron and consequent 130

sag in the lower reach or between the rollers 4 and 3, taking up any portion of the sag between the roller 3 and the swinging frame. By thus supporting the belt or apron throughout the remainder of its path of travel, the bight formed between the roller 3 and the swinging frame may be maintained uniform, whereas if sag were permitted elsewhere in the belt or apron, the compression of the bight about the binder would take up such incidental sag or slack, and serve to vary the size of the operating bight.

From the above description, it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise but one of several modes of putting the invention into effect and the invention is therefore claimed in any of its forms or modifications within the legitimate and valid scope of the appended claims.

Having thus described my invention, I claim:

1. In a cigar rolling machine and the like, a main frame, a series of three rollers mounted therein in parallel spaced relation, an endless traveling apron extending about the outermost rollers with its upper run en-

gaging the intermediate roller, a supporting guide for the lower run of the apron extending substantially from one extreme roller to the other whereby such bottom run will be supported without sag; a supporting guide for the upper run of the apron between one of the extreme rollers and the intermediate roller to eliminate sag, the top run of the apron being formed into a bight between the intermediate roller and the other extreme roller to receive the material to be rolled, a swinging guide frame located intermediate the medial and the extreme roller contiguous to said bight and over which the apron passes, said swinging frame being adjustable toward and from the intermediate roller to contract and release said bight, means for actuating the guide frame and means for advancing said apron.

2. In a cigar rolling machine and the like, a series of three rollers mounted in substantially a common plane, an endless apron surrounding the series of rollers, said apron having therein an excess of material forming a dependent bight intermediate the medial roller and one of the terminal rollers of the series in which the material to be operated upon is deposited, supporting means for the apron whereby the size of the bight will be unaffected by the weight of the belt, a movable guide member for said apron located intermediate the medial roller and the other terminal roller contiguous to said bight, by the adjustment of which the bight is contracted and opened, and means for advancing the apron and means for adjusting said guide member.

In testimony whereof, I have hereunto set my hand this 18th day of February A. D. 1921.

ALLEN NOEL.
